HIGH-PRESSURE RECIPROCATING COMPRESSOR

Application filed September 29, 1928, Serial No. 309,266, and in Switzerland November 8, 1927.

This invention relates to high pressure reciprocating compressors of the kind in which power is transmitted from the piston of the driving machine through an oscillating column of liquid to an intermediate or driving piston which actuates the compressor piston.

According to the present invention in a compressor of the kind described means are provided for rendering inoperative a portion 10 of the liquid column so as to vary the length of the stroke of the compressor piston or pistons without changing the mid point about which such compressor pistons reciprocate. Preferably the portion of the liquid column 15 to be rendered inoperative is diverted through a by-pass pipe into a chamber in which it transmits no power. Both the intermediate piston and the piston of the driving machine may be in the form of double-acting stepped 20 pistons, corresponding liquid columns on opposite sides of these pistons being connected by by-pass pipes. Alternately, either of these pistons may be a simple double-acting piston and the other a stepped piston. The conduits 25 and by-pass pipes for the liquid columns are provided with stop valves to control the passage of the liquid and those stop valves which are to be opened or closed simultaneously may be provided with a common control mechanism.

The invention may be carried out in various ways but three arrangements according thereto are illustrated by way of example as applied to a two-stage compressor in the accompanying drawings in which

Figure 1 shows the position of the stop valves to produce the maximum length of stroke of the compressor pistons, this length of stroke being indicated by the dotted end 40 positions of the pistons,

Figures 2 and 3 illustrate the positions of the valves necessary to produce a shorter stroke,

Figures 4 and 5 show modifications of the arrangement illustrated in Figures 1-3, and

Figure 6 is a diagram of lengths of piston strokes.

In the arrangement of Figures 1, 2 and 3, the double-acting double stepped piston 7 of the driving machine is adapted to reciprocate

within a cylinder 1 and thereby to impart oscillatory movement to a liquid column divided into four parts 2, 3, 4 and 5 disposed within the cylinder. The intermediate piston 13 reciprocates within its cylinder 12 and is 55 mounted on a piston rod 18 on which are also mounted the compressor pistons 20 and 22 reciprocating respectively within the cylinders 19 and 21 of the stages I and II. The liquid columns 2 and 3 are connected by means of conduits 8 and 9 with one end of the intermediate cylinder 12 while the columns 4 and 5 are connected by means of conduits 14 and 15 with the opposite end of the cylinder 12. The conduits 8 and 9 are provided with stop 60 valves 10 and 11 respectively and the conduits 14 and 15 with valves 16 and 17.

A by-pass pipe 24 connects the liquid columns 2 and 5 and is provided with a stop valve 23 while the liquid columns 3 and 4 70 are connected by a by-pass 25 having a stop valve 26.

The stop valves 10 and 17 may be operated individually, or if desired they may be actuated simultaneously by means of a common control rod 27. Similarly the simultaneous operation of the stop valves 11 and 16 75 may be effected by means of a common control rod 28.

Assuming that the valves 10, 11, 16, 17, 80 23 and 26 are in the positions shown in Figure 1, the operation of the apparatus is as follows.

The working surface F of the piston 7 of the driving machine, for each direction of motion, comprises the smaller surface f_1 and the larger surface f_2 . When the piston 7 moves towards the left in Figure 1, the surfaces f_1 and f_2 act respectively on the liquid columns 2 and 3 and force them through the conduits 8 and 9 into the left-hand end of the cylinder 12 thus forcing the intermediate piston 13 towards the right and effecting the compression of the medium within the right-hand ends of the cylinders 19 and 21. On 95 the return stroke of the piston 7 the same area $F=f_1+f_2$ acts on the liquid columns 4 and 5 and forces them through the conduits 14 and 15 respectively into the right-hand end of the cylinder 12 thus effecting the com- 100

pression of the medium within the left-hand ends of the cylinders 19 and 21. As can be seen from Figure 1, the stop valves 23 and 26 in the by-pass pipes 24 and 25 are closed 5 and the length of the stroke of the compressor pistons 20 and 22 is at a maximum.

If now it is desired to reduce the length of the stroke of the compressor pistons the effective volume of the liquid column must be reduced, that is a part of the liquid column must be rendered inoperative. To this end the stop valves 10 and 17 are brought 10 into the closed position shown in Figure 2 and the valve 23 opened, thus rendering the 15 surface f_1 and the columns 2 and 5 ineffective. With the valves in this position movement of the piston 7, for example towards the left in Figure 2, forces the liquid column 3 through the conduit 9 and valve 11 20 into the left-hand end of the cylinder 12. On the other hand, the liquid displaced by the surface f_1 merely flows through the by-pass pipe 24 into the space occupied by the column 5 and does no work on the intermediate piston 13. Consequently the piston 13 25 is only displaced as far as the end positions indicated in dotted lines in Figure 2.

On the return stroke of the piston 7 a similar action takes place, the reduction in 30 the length of the stroke of the compressor pistons being equal to s_0 in each direction, that is the total reduction equals $2xs_0$, while the mid point about which the compressor pistons reciprocate remains unchanged.

If it is desired to reduce the length of the stroke still further the surface f_2 of the piston 7 may be rendered ineffective by closing the valves 11, 16 and 23 and opening the valves 10, 17 and 26 thus putting the liquid 35 columns 3 and 4 out of action (Figure 3). This reduces the length of the stroke of the compressor pistons to the dimensions indicated by the dotted lines in Figure 3.

In the modified arrangement illustrated 40 in Figure 4, the piston 7 of the driving machine is a simple double-acting piston while the intermediate piston 13 is in the form of a double-acting stepped piston. The piston 7 only acts on two, instead of four, liquid 45 columns, that is the columns 30 and 31 of which the column 30 acts through a conduit 32 on the smaller right-hand surface of the piston 13 and through a conduit 33 on the larger right-hand surface thereof while the column 31 acts through conduits 36 and 37 50 on the smaller and larger left-hand surfaces respectively of the piston 13. The conduits 32, 33, 36 and 37 are provided with stop valves 34, 35, 38 and 39 respectively 55 and the two ends of the cylinder 12^a of smaller diameter are connected by a by-pass pipe 40 while the ends of the larger cylinder 12^b are connected by a by-pass pipe 41. These by-pass pipes are provided with stop 60 valves 42 and 43 respectively. The valves 65

34, 38 and 42 may be operated by a common control mechanism as also may the valves 35, 39 and 43.

In order that a variation in the length of stroke of the compressor piston may be rendered possible, the dimensions of the areas and strokes of the pistons 7 and 13 are such that the length of the stroke of the compressor pistons 20 and 22 is greatest when the columns 30 and 31 act on the smallest 70 surface of the intermediate piston 13, that is when the conduits 32 and 36 and the by-pass pipe 41 are open, the conduits 33, 37 and 40 being closed (Figure 4).

In the drawing (Figure 4) the larger surface of the piston 13 has twice the area of the smaller surface so that in order to reduce the length of the stroke of the pistons 20 and 22 to one-half the columns 30 and 31 must act on the larger surface alone, the smaller 80 surface being rendered inoperative. Again, if the length of the stroke is to be reduced to one-third of the maximum value the columns 30 and 31 must be made to act on the larger as well as on the smaller surface of the 85 piston 13. Thus to reduce the stroke to one-half the valves 34, 38 and 43 must be closed and the valves 35, 39 and 42 open, while to reduce the length of the stroke to one-third of the maximum the valves 34, 35, 38 and 39 90 must be opened and the valves 42 and 43 closed.

The variation in the length of the stroke may be further graduated by making both the intermediate piston and the piston of the 95 driving machine in the form of stepped pistons, the number of variations being dependent upon the number of steps. An example of an apparatus constructed in this way is illustrated diagrammatically in Figure 5.

In this arrangement both the liquid columns 2 and 3 are in communication with each of the intermediate cylinder spaces 45 and 46 while the columns 4 and 5 are both in communication with each of the intermediate cylinder spaces 47 and 48, the individual conduit connections meeting at 49 and 50 as shown. These conduits are controlled by stop valves 51, 52, 53, 54 and 55, 56, 57 and 58 which are arranged as shown in the figure. In addition, the cylinder spaces 45 and 48 are connected by a by-pass pipe 40 while the spaces 46 and 47 are connected by a by-pass pipe 41, these by-passes being provided with stop valves 42 and 43 respectively. The cylinder spaces 2, 5 and 3, 4 are similarly connected by by-pass pipes 24 and 25 respectively, these by-passes being provided with stop valves 23 and 26 respectively.

The pistons 7 and 13 are so dimensioned that the length of the stroke of the compressor pistons 20 and 22 is at a maximum when the larger and smaller surfaces of the piston 7 displace the liquid columns 2 and 3 simultaneously and cause them both to act

on the smaller surface of the piston 13 alone. To bring this about the valves 51, 52, 53, 55, 56, 58 and 43 must be opened and the valves 23, 26, 42, 54 and 57 closed. Conversely, the 5 length of the stroke of the pistons 20 and 22 is at a minimum when the liquid column 2 alone is displaced into both the spaces 45 and 46 in one direction and the column 5 alone is displaced into both the spaces 47 and 10 48 in the other direction, while the columns 3 and 4 oscillate in the by-pass 25 without transmitting power. To effect this the valves must be in the positions shown in Figure 5.

It will be appreciated that the invention 15 provides a number of possible ways of varying the length of the stroke of the compressor pistons without changing the mid-point about which these pistons reciprocate. Thus, for example, the arrangement may be 20 such that only a part of the liquid displaced by the piston of the driving machine acts on the intermediate piston while the remainder oscillates in a by-pass pipe without transmitting power (Figures 1-3). Alternatively, 25 the whole of the liquid displaced by the piston of the driving machine may be made to act on the intermediate piston and the variation in stroke may be obtained by altering the volume of the intermediate cylinder 30 (Figure 4). Again, the liquid column actuated by the piston of the driving machine may be divided into a number of part columns, and the length of stroke varied by putting one or more of these columns out of action, and also by varying the volume of the cylinder containing the intermediate piston on which these columns act (Figure 5). As 35 shown in Figure 6, the maximum length of stroke s of the compressor pistons can be thus reduced to values such as s_1 , s_2 etc. without changing the mid-point m about which these 40 pistons reciprocate.

I claim:

1. A compressor-plant, comprising a reciprocating-piston compressor, a driving engine having a cylinder and a reciprocating piston, another piston intermediate the engine and the compressor and structurally connected to the compressor piston, a cylinder therefor, a fluid-conduit between the piston of the driving engine and the intermediate piston, said connection having a liquid column therein, and means for rendering inoperative a portion of the said liquid column on occasion.
2. A compressor-plant, comprising a reciprocating-piston compressor, a driving engine having a cylinder and a reciprocating piston, another piston intermediate the engine and the compressor and structurally connected to the compressor piston, a cylinder therefor, a fluid-conduit between the piston of the driving engine and the intermediate piston, said connection having a liquid column therein, and a by-pass pipe in said engine connected to said liquid column and having means

for diverting a portion of the liquid column out of communication with said intermediate piston.

3. A compressor-plant, comprising a reciprocating-piston compressor, a driving engine having a cylinder and a double acting stepped reciprocating piston, another piston intermediate the engine and the compressor and structurally connected to the compressor piston, a cylinder therefor, liquid columns in the respective cylinders on both sides of said driving engine piston and said intermediate piston, and respective by-pass conduits connected on the respective stepped ends of said stepped piston, said by-passes having means by which the respective columns of liquid can be shunted as desired on occasion. 70 75

4. A compressor-plant, comprising a reciprocating-piston compressor, a driving engine having a cylinder and a double-stepped double acting piston therein, a double-acting piston connected intermediate the compressor and engine to the compressor pistons, a cylinder therefor, liquid containers inserted between the piston of the driving engine and the intermediate piston, and by-pass pipes connecting corresponding liquid columns on opposite sides of the said pistons. 80 85 90

5. A compressor-plant, comprising a reciprocating-piston compressor, a driving engine having a cylinder and a reciprocating piston, another piston intermediate the engine and the compressor and structurally connected to the compressor piston, a cylinder therefor, a fluid-conduit between the piston of the driving engine and the intermediate piston, said connection having a liquid column therein, and a by-pass pipe in said engine connected to said liquid column and having means for diverting a portion of the liquid column out of communication with said intermediate piston, said means comprising a stop-valve in said pipe. 95 100 105

6. A compressor-plant, comprising a reciprocating-piston compressor, a driving engine having a cylinder and a double acting stepped reciprocating piston, another piston intermediate the engine and the compressor and structurally connected to the compressor piston, a cylinder therefor, liquid columns in the respective cylinders on both sides of said driving engine piston and said intermediate piston and respective by-pass conduits connected on the respective stepped ends of said stepped piston, said by-passes having means by which the respective columns of liquid can be shunted as desired on occasion, said means comprising stop-valves therein on opposite sides of the stepped driving-engine piston through which the liquid can be respectively passed on occasion. 110 115 120 125

7. A compressor-plant, comprising a reciprocating-piston compressor, a driving engine having a cylinder and a double acting 130

stepped reciprocating piston, another piston intermediate the engine and the compressor and structurally connected to the compressor piston, a cylinder therefor, liquid columns in the respective cylinders on both sides of said driving engine piston and said intermediate piston, and respective by-pass conduits connected on the respective stepped ends of said stepped piston, said by-passes having means by which the respective columns of liquid can be shunted as desired on occasion, said means comprising stop-valves therein, said stop-valves being arranged to connect corresponding liquid columns on opposite sides of the intermediate and driving-engine pistons.

8. A compressor-plant, comprising a reciprocating-piston compressor, a driving engine having a cylinder and a double acting stepped reciprocating piston, another piston intermediate the engine and the compressor and structurally connected to the compressor piston, a cylinder therefor, liquid columns in the respective cylinders on both sides of said driving engine piston and said intermediate piston, and respective by-pass conduits connected on the respective stepped ends of said stepped piston, said by-passes having means by which the respective columns of liquid can be shunted as desired on occasion, said means comprising stop-valves therein, said stop-valves being arranged to connect corresponding liquid columns on opposite sides of the intermediate and driving-engine pistons, and means for simultaneously controlling said stop-valves.

In testimony whereof I have affixed my signature.

CHARLES SCHAER.
